UNITED STATES PATENT OFFICE.

JAMES LEON WILLIAMS, OF NEW YORK, N. Y., ASSIGNOR TO THE DENTISTS' SUPPLY COMPANY, A CORPORATION OF NEW YORK.

ARTIFICIAL TOOTH.

1,139,615.

Specification of Letters Patent. Patented May 18, 1915.

Application filed March 7, 1914. Serial No. 823,073.

To all whom it may concern:

Be it known that I, JAMES LEON WILLIAMS, citizen of the United States, and resident of New York, county of New York, and State of New York, have invented an Improvement in Artificial Teeth, of which the following is a specification.

The object of my invention is to provide a construction of artificial tooth which shall have certain characteristic surface constructions capable of producing in use an approximation to the appearance of natural teeth. In artificial teeth, as they have been heretofore constructed, and more particularly in respect to the front teeth, namely those located between the bicuspids and which are more readily exposed in the act of talking, the porcelain of the labial surfaces of the teeth have invariably been made with a comparatively smooth glossy appearance which so reflects the light as to appear unnaturally brilliant and obtrusive, thereby making their artificial nature more readily apparent. It is desirable that the artificial front teeth shall be so constructed, not only as to shape and color, as to resemble natural teeth, but the objectionable characteristics of the glossy porcelain shall be subdued by surface structural features which shall so break up the reflected rays from the teeth that the artificial appearance is greatly subdued and the general effect to the eye of an observer shall more nearly approximate the characteristic appearance of natural teeth.

My invention consists in an artificial tooth having its front or labial surface provided with transversely arranged portions in more or less irregular manner which shall so break up the reflected light as to prevent a brilliant reflection from the medial portions of the labial surface.

More specifically considered, my invention comprises a tooth having its labial or front surface provided with vertical shallow grooves approximating those of natural teeth crossed by a plurality of shallow grooves or irregular surface portions of relatively small cross section which, while not obtrusive to the eye, act to split up or break the reflections from the tooth surface to soften the brilliancy thereof more particularly at the medial portion of the front or labial surface.

My invention also comprehends features of construction which, with those above

stated, will be more fully understood by reference to the accompanying drawings, in which:

Figure 1 is a front elevation of an artificial tooth embodying my improvements; 60 Fig. 2 is a vertical sectional view of the same on a larger scale; Figs. 3, 4 and 5 are transverse sections of the same taken on lines $x-x$, $y-y$ and $z-z$ respectively of Fig. 2; and Fig. 6 is a front elevation of an artificial tooth embodying a modification of my invention.

A is the body of the tooth and may be made of any of the usual bisque compositions vitrified to form a porcelain tooth having a particular shape according to whether the tooth is for the upper or lower jaw and whether incisors or canine teeth constituting the front teeth of the mouth. The general shape of the teeth, in so far as their application to a plate or for otherwise being secured in the mouth, whether in bridge work or crown work or otherwise, is immaterial to my invention, as the particular improvements here set out are especially directed to 70 the front or labial surfaces of the teeth which are exposed in talking. I prefer to arrange at the upper portion of the tooth, a plurality of wide curved transverse ridges D to approximate the formation adjacent to 75 the root of the tooth and which come close to the gums in use. Between these ridges D and the biting edge C, the front surface may be provided with vertical grooves which are widely separated and of shallow depth approximating the vertical grooves found in natural teeth, such grooves being indicated at F, F, in Fig. 1, wherein a front upper incisor is shown. In the medial belt or portion of the front or labial surface of the 80 tooth, namely that portion below the transverse ridges D and the lower portion of the tooth, I provide a large number of transversely arranged irregularities or striations of relatively small individual depth, indicated for example, at E in Figs. 1 to 4, 85 inclusive, and at E' in Fig. 5. In the preferred form, these irregularities E are best formed by providing transverse grooves of small cross section and irregularly disposed 90 transversely so that the surface is irregular and the planes of the surface are so variable that the reflected light is broken up in such a manner as to destroy the objectionable brilliancy of the porcelain surface. More-

100 105 110

over, these transverse grooves or striated irregularities E extend across the vertical grooves F, and this further changes the depth of the grooves and angles of the surfaces. The cross section of the tooth at different levels will provide a front or labial surface of different configuration, not only in the general cross section of the tooth, but in the reflecting surface thereof, as will be apparent by reference to Figs. 3, 4 and 5, where the irregularities shown at E in Figs. 4 and 5 are characteristically different from the irregularities shown at D in Fig. 3.

When a tooth having the above structures is employed in the mouth, it is manifest that whether the labial surface is moistened or not, the reflection is so greatly subdued by having the reflected light rays caused to diverge in so many different directions that the heretofore brilliant reflection of the porcelain has been so modified that to the observer the tooth has an appearance which closely approximates the natural tooth. This natural appearance is, moreover, increased in actual use of the tooth, over the forms of artificial teeth heretofore in use, in that the labial surface thereof becomes more or less coated with the secretions of the mouth and which to a slight extent are more readily supported by the fine irregular surface formed by the transverse irregularities E to soften the reflected light.

In view of the fact that the transverse irregular grooving or striations E is made upon a convex surface, both vertically and transversely, aside from other irregularities caused by the vertical grooving F of the tooth, it is manifest that there will be but a very small surface at any one place to cause reflections of parallel rays of light; and it is therefore apparent that the reflected light must necessarily be materially subdued, and moreover, the surface of the teeth will be devoid of that uniformity which has heretofore been so objectionable a characteristic of artificial teeth.

In the modified form of my invention, shown in Fig. 6, I have formed the transverse irregularities or striations by surfaces having such fine stippling as to produce a more or less frosted appearance and thereby break up the reflected light without as great a depth of irregularities as in the case of Figs. 1 and 2. This stippling or frosted effect is preferably formed in transverse bars, as in the case of Fig. 1, and while it is indicated in Fig. 6 in the form of dots by way of illustration, it is manifest that it may be formed by depressions or minute

projections, though the surface itself being of porcelain would be of the usual glossy appearance. The reflections of light, however, will be greatly dispersed and will operate in more or less the same manner as the irregularities shown in Figs. 1 and 2, thereby giving to the teeth the more natural dullness of natural teeth.

In the particular illustration shown in the drawings, the tooth indicates what is known as a "pin" tooth, namely, one having metallic pins projecting at the rear, whereby they may be attached to the rubber or other plate which is to fit the jaw. This is only by way of example, as in the case of crown teeth the pin would be at the upper portion, or the tooth may be applied to a plate by grooves or any other of the well known manners of attachment of artificial teeth in common use. My invention is applicable to any artificial front teeth, irrespective of the shape of the back or means of attachment for use in the mouth, whether to natural teeth by use of the bridge work and crowns, by direct application to the jaw or by attachment to a plate.

Having now described my invention, what I claim as new and desire to secure by Letters Patent, is:

1. An artificial tooth having its entire labial portions formed with a glossy surface said surface provided at and near one end with large transverse ribs and at and adjacent its other or biting end with a relatively smooth reflecting surface and also having its middle surface between the end portions formed with a plurality of transversely arranged shallow light dispersing striations blending into the large transverse rib portions and terminating at a distance from the smooth reflecting surface of the biting end of the tooth.

2. As an article of manufacture, an artificial tooth in which its labial surface at and immediately adjacent to its biting end is formed smooth and reflecting and the medial portion of said labial surface formed with irregularly disposed light dispersing portions to reduce the brilliancy of the said labial surface at a distance from the biting end, said light dispersing portions separated from said biting end by the smooth reflecting surface aforesaid.

In testimony of which invention, I hereunto set my hand.

JAMES LEON WILLIAMS.
